AUGUST TAPPE, OF JOHNSTOWN, NEW YORK.

Letters Patent No. 87,444, dated March 2, 1869.

IMPROVEMENT IN SMOKING-PIPES AND CIGAR-HOLDERS.

The Schedule referred to in these Letters Patent and making part of the same.

To all whom it may concern:

Be it known that I, AUGUST TAPPE, of Johnstown, in the county of Fulton, and State of New York, have invented a new and useful Improvement in Smoking-Pipes and Cigar-Holders; and I do hereby declare that the following is a full, clear, and exact description thereof, which will enable others skilled in the art to make and use the same, reference being had to the accompanying drawing, forming part of this specification, in which the drawing represents a sectional view of a cigar-holder or pipe-stem provided with my improved attachment.

The object of this invention is to provide a new attachment to the stems or mouth-pieces of pipes and cigar-holders, whereby the tobacco-juice is prevented from entering the mouth-piece, and from thereby injuring the health of the smoker.

The invention consists in the application, within the stem, of a perforated conical tube, suspended from a perforated diaphragm, and of a perforated tube, projecting upward above said diaphragm, so that by the said tubes the juice will be arrested, and only smoke allowed to pass into the mouth-piece.

A, in the drawing, represents the mouth-piece of a cigar-holder or pipe.

B is the stem of the same.

In the drawing, the black lines represent a cigar-holder, while the red lines show the same parts applied to a pipe.

In the upper part of the stem B is arranged a sheet-metal or other diaphragm, *a*, which may be secured in any suitable manner, it being represented as fastened to a tube, *b*, that is, by means of a flange, *c*, suspended from the upper edge of the stem.

The plate *a* is perforated in the centre, and from its under side is suspended a perforated conical tube, *C*,

as shown, while from its upper face may, if desired, project upward, a short tube, *d*, which is open on top.

To the lower end of the mouth-piece A is secured a tube, *D*, which can be fitted into the upper part of the stem, or into the tube *b*, as shown, so that its closed end fits upon the plate *a*, as shown.

From the bottom, *e*, of the tube *D*, projects upward a tube, *E*, which is open at its lower end, and which fits over the tube *d*, so as to form an upward extension of the cone *C*.

The upper end of the tube *E* may be enlarged, as shown, and is perforated at the junction of the enlarged and cylindrical portions.

The smoke can pass from the lower part of the stem, through the cone *C* and tube *E*, into the mouth-piece, while the juice cannot pass through the fine apertures of *C*, and will therefore remain in the stem. Should, however, some enter the cone *C*, it will be arrested in the tube *E*.

By having the tube *E* attached to the mouth-piece, and the cone *C* to the stem, as described, the pieces can be readily taken apart for cleaning-purposes.

Instead of being secured in the stem, the plate *a* may be arranged in the shank of the bowl, and the tube *D*, on the stem of a pipe.

Having thus described my invention,

I claim as new, and desire to secure by Letters Patent—

The hollow perforated cone *C*, perforated tube *E*, and diaphragm *a*, when arranged within the stem, or other part of a cigar-holder or smoking-pipe, substantially as herein shown and described, for the purpose specified.
